UNITED STATES PATENT OFFICE.

JOHN ILLINGWORTH, OF BATLEY, COUNTY OF YORK, ENGLAND.

APPARATUS FOR CARBONIZING VEGETABLE FIBERS.

SPECIFICATION forming part of Letters Patent No. 430,127, dated June 17, 1890.

Application filed December 10, 1889. Serial No. 333,246. (No model.) Patented in England December 20, 1888, No. 18,614.

To all whom it may concern:

Be it known that I, JOHN ILLINGWORTH, a subject of the Queen of Great Britain, residing in Batley, Yorkshire, England, have invented certain new and useful Improvements in Machinery for Carbonizing and Drying Fabrics and Fibers, (for which I have received a patent in England, No. 18,614, dated December 20, 1888,) of which the following is a specification.

My invention relates to machinery to be employed for carbonizing or separating and destroying cotton or other vegetable matter contained in rags or other like material. In carrying out my invention I employ a long cylinder composed of sheet-iron, steel, or other suitable material. Fabrics or fibers to be operated upon are placed into this cylinder, which is arranged to be lower at the delivery end than at the feeding end. The cylinder is mounted upon rollers which are driven by suitable gearing for the purpose of giving rotary motion to the said cylinder. The delivery end of the cylinder, or the whole of said cylinder, may be perforated, and the fiber to be fed therein is placed in a hopper, and by means of a pair of feed-rollers the material to be operated upon is fed automatically into the machine. At the delivery end or front of the machine I introduce gases, which are admitted by means of a pipe from a retort in close proximity to the machine. Projecting from the inside of the cylinder are a number of teeth or spikes so arranged that as the cylinder revolves the spikes gather up the fabrics and carry them around until at a given point the fabrics fall off the spikes. Consequently as the fabrics are thus agitated within the cylinder the gases freely impinge upon every part, thereby thoroughly carbonizing or destroying the vegetable matter, leaving the animal fiber intact. As the cylinder is placed at an inclination, the fabrics travel slowly forward through the cylinder. The apparatus is placed within a room or surrounded by suitable brick-work or iron frame-work, and the temperature is got up to any required degree by means of a fire or a suitable arrangement of steam or hot-air pipes.

In order that my invention may be better understood, I will now proceed to describe the

same more fully, and for that purpose make reference to the accompanying sheets of drawings, illustrative thereof, wherein—

Figure 1 is a sectional elevation of a carbonizing-machine constructed according to my invention, and Fig. 2 a cross-section of same through the line 1 2 of Fig. 1. The driving mechanism is shown in Fig. 3, while Fig. 4 is a section through line 3 4 in Fig. 1.

A represents the metal cylinder, the outer side of which is provided with rings or flanged pulleys B, resting upon smaller anti-friction pulleys C, the latter of which support the said cylinder and allow it to revolve freely thereon without much friction. The cylinder has also placed onto it a toothed wheel D in gear with a pinion-wheel E, by which the cylinder is made to revolve. The pinion-wheel E, fixed upon shaft F, receives its rotary motion by means of worm-wheel G and worm H, fixed upon the main driving-shaft I of the machine.

J is a hopper, in which are two toothed feed-rollers K and L, caused to revolve by means of worms and wheels a and b, driven by means of the chain M from the pulley N, fixed upon shaft F. The rags or other fibrous material to be carbonized is introduced into the hopper J and is drawn into the machine by the feed-rollers K and L, which are caused to revolve, as indicated by arrows, in such a manner as to drag or draw the fiber into the cylinder A, and when the fiber enters the said cylinder the spikes O carry the said fiber around until they reach near the top of the cylinder, when by their own weight they fall again to the bottom of the cylinder, and this is continually going on so long as the cylinder revolves. Consequently the fabrics are freely and thoroughly agitated, and, as the outlet end of the cylinder is placed lower than the inlet, it follows that as the cylinder revolves the fabrics will traverse out at the opposite end.

The carbonizing-gases to destroy the vegetable matter in the rags or other fiber are generated in the retort P, such gases being conveyed by the pipe Q into the annular space R (see Fig. 2) left between the brick-work S and the outside of the revolving cylinder A, and as the cylinder is perforated, as shown by letter c, the fumes of the gases pass

through the said perforations into the revolving cylinder and intermingle with the fabrics which are being freely carried about and agitated by the spikes. Thus the vegetable matter will be thoroughly destroyed, but the animal fiber will remain intact.

Instead of introducing the gases at the delivery end of the machine, as shown and described, the said gases may be introduced by 10 pipe T, as shown by dotted lines in Fig. 1, at the feeding end of the machine, in which case the gases will travel through the whole length of the cylinder. The fumes of the gases may be drawn out of the cylinder and annular 15 space by means of an exhaust-fan.

For effectually carbonizing fabrics and fibrous materials, it is necessary that the cylinder and chambers should be heated at suitable temperatures, and this I accomplish by 20 means of a furnace, which may be made in the grate U, the heat therefrom passing along the flue V, whereby the metal floor-plates W will become heated, which heat is radiated or given off to the various parts of the brick- 25 work and cylinder, and if necessary the floor-plates W may be perforated, or instead of employing a furnace for heating the parts a number of steam or hot-air pipes may be used.

Although I have shown and described this 30 machine as being employed for carbonizing or separating vegetable from animal matter, the machine is equally well adapted for drying wool, cotton, or other fibrous materials; but when so employed the use of gas would 35 not be required.

I claim as my invention—

1. The combination, with a hollow chamber provided with partitions and means—such as a furnace—for heating the air within the same, of a revoluble perforated cylinder supported in said chamber and provided with spikes for raising the rags, a hopper and revoluble feed-rolls for feeding the rags into one end of the cylinder, and a retort connected to said chamber for supplying carbonizing-gases to the cylinder and to that portion of the chamber with which the perforations communicate, substantially as and for the purpose set forth. 40

2. The combination, with a hollow heated 50 chamber provided with partitions and with a space R for carbonizing-gases, of a revoluble perforated cylinder passing through said space and provided with spikes for raising the rags, a hopper and revoluble feed-rolls 55 for feeding the rags into one end of the cylinder, and a retort for supplying carbonizing-gases to said space R, with which the said perforations in the cylinder communicate, substantially as and for the purpose set forth. 60

In witness whereof I have hereunto signed my name in the presence of two subscribing witnesses.

JOHN ILLINGWORTH.
